The ornamental design for a refrigerator with upper French style doors, as shown and described.

DESCRIPTION

FIG. 1 is a top right perspective view of a refrigerator including closed, upper French style fresh food compartment doors and a lower freezer door/drawer, showing our new design;

FIG. 2 is a front elevational view of the refrigerator of FIG. 1 with the upper French style doors closed;

FIG. 3 is an elevational view of the right side of the refrigerator of FIG. 1, with the left side elevational view being a mirror image thereof;

FIG. 4 is a top plan view of the refrigerator of FIG. 1;

FIG. 5 is a top right perspective view of the refrigerator of the invention, with the upper French style doors shown open;

FIG. 6 is a front elevational view of the refrigerator of FIG. 5;

FIG. 7 is a right side elevational view of the refrigerator of FIG. 5, with the left side elevational view being a mirror image thereof; and,

FIG. 8 is a top plan view of the refrigerator of FIG. 5. The broken lines in FIGS. 1-8 showing door handles and hinges, the pivoting mullion carried by one of the upper French style doors as shown in FIGS. 2, 5, 6 and 8, and the upper fresh food compartment mounted mullion guide of FIGS. 5-8 are for illustrative purposes only and form no part of the claimed invention.
